United States Patent Office.

A. G. BURTON, OF ROCHESTER, NEW YORK.

Letters Patent No. 99,400, dated February 1, 1870.

IMPROVEMENT IN LOCK-SPINDLES FOR SAFES

The Schedule referred to in these Letters Patent and making part of the same.

To all whom it may concern:

Be it known that I, A. G. BURTON, of the city of Rochester, county of Monroe, and State of New York, have invented a certain new and Improved Spindle-Connection for Safes; and I do hereby declare that the following is a full and exact description of the same, referring to the accompanying drawings, in which—

Figure 1 is a section of a portion of a safe door, showing my improvement.

Figure 2, a view showing an elevation of the gearing embedded in the plating.

Figures 3 and 4, detail views.

Like letters of reference indicate corresponding parts in all the figures.

My invention consists in so arranging the spindle, as hereinafter described, as to prevent a direct communication through the safe.

In the drawings—

A represents a portion of the safe-door, which may be composed of the ordinary welded steel and iron plates *a a*, or constructed in any other desired manner.

Instead of an ordinary spindle, running straight through the safe from outside to inside, I employ two short spindles, B B, one opening from the outside and the other from the inside, and meeting at any intermediate position in the plating. These spindles do not come opposite each other, but at suitable distance apart, as shown, thereby making an irregular communication through the door, so that in drilling from the outside, the passage at the end will strike abruptly against the closed plating of the safe.

A connection is made between the spindles B B by means of gears *b b*, lever-work, or any other arrangement, by which motion may be imparted to the inner by turning the outer one.

When the inner spindle is to be connected with the lock-work, the gears will be found most convenient, as a continuous rotary movement as great or greater than a complete circle, must take place, but when it is attached to the heavy bolt-work of the door to throw it, the lever-work before spoken of may answer, as only a small movement is required.

The arrangement, as above described, is applicable either to operate the lock-work or heavy bolt-work.

If desired, also, the gears may be made of unequal sizes to vary the action; or intermediate gears may be used between those connected with the spindle, by which means the spindles may be located at greater distances apart, thereby increasing the difficulty of inserting gunpowder, or otherwise making a connection through the safe.

The spindles, next the gears, are preferably provided with reverse conical enlargements, *c c*, the object of which is to prevent their being drawn or driven

out endwise. If desired, however, these may be dispensed with, and the spindles made straight.

The object of this invention is to prevent a direct spindle connection through the door from outside to inside, such as is now universally employed in safes.

The spindle is the most vulnerable point about a safe. It is difficult to make it so strong as not to be drawn out or driven in. If it escapes this ordeal, it is liable to be softened by the heat of a blow-pipe, and drilled out.

By breaking the connection of the opening of the spindle, as described, the drilling of the outer portion of the spindle will only strike against the solid plating inside, which cannot be drilled through. The turn of the passage at that point, and the gearing embedded, will prevent the reaching of the inner passage. And if gunpowder is used, it will blow out, or, at any rate, it cannot act so effectively in the crooked passage as it would in a straight one.

If desired, the spindles, one or both, may be screwed into the gears, as shown at *d*, fig. 4, and retained by a key, *f*. This will allow the spindles to be inserted from the outside of the door, and will also adapt the length of the spindles to different thicknesses of the safe.

The dial C, upon the exterior of the door, is made in the form of a ring, leaving an open space, *g*, surrounding the spindle. The spindle also is provided with several pointers or index-hands *h h*, to be used in connection with the figures upon the dial.

By leaving the space *g*, in the dial, no chance is left to enable a burglar to attach an indicating-apparatus to the spindle, to show the position of the wheels of the lock.

In ordinary locks this space is covered by the escutcheon of the knob, and expert burglars, by a visit prior to the one for the opening of the safe, attach a fine apparatus to the spindle, which, in the ordinary use of the lock, leaves marks upon the surface beneath of the position of the wheels when set. By leaving this space entirely open, no such attachment can be made without detection.

By the use of several pointers or index-hands, the burglar is at a loss to know which was used in making the combination. They also enable the same combination to be set by the use of several pointers.

What I claim, is—

The arrangement of the gear-wheels *b b* within the body of the door, in combination with a lock or bolt-work arranged on the back side of the door, and the knob-spindle out of line with the lock or bolt-work spindle, substantially as specified.

In witness whereof, I have hereunto signed my name, in the presence of two subscribing witnesses.

Witnesses: A. G. BURTON.
